UNITED STATES PATENT OFFICE.

DAVID H. STROUD, OF PHILADELPHIA, PENNSYLVANIA.

ART OF FINISHING CUT-PILE RUG OR CARPET FABRICS.

1,206,048.

Specification of Letters Patent. Patented Nov. 28, 1916.

Application filed July 30, 1915. Serial No. 42,672.

To all whom it may concern:

Be it known that I, DAVID H. STROUD, of Philadelphia, in the county of Philadelphia and State of Pennsylvania, have invented 5 certain new and useful Improvements in the Art of Finishing Cut-Pile Rug or Carpet Fabrics, whereof the following is a specification, reference being had to the accompanying drawings.

10 In said drawings, I have illustrated diagrammatically the conditions which attend different stages in my process, but it must be understood that the illustrations are largely symbolic, and are intended only for 15 explanatory purposes, as distinguished from being accurate illustrations of actual fabric. Each of said drawings is an exaggerated cross sectional view through a portion of a rug fabric, indicating conventionally some 20 of the physical features as they exist at selected periods, or steps, in the course of treatment.

Thus, Figure I, indicates the fabric in its initial condition, *i. e.*, after the operations of 25 weaving and cutting of the pile have been performed; Fig. II, indicates the conditions at the conclusion of the washing step; Fig. III, indicates the conditions at the conclusion of the scraping step; Fig. IV, indicates 30 the finished article.

My invention is especially contemplated for use in connection with woolen chenille pile fabrics, though not necessarily restricted thereto. Its object is to give a peculiar 35 soft finish comparable to that found in the finest type of antique oriental rugs, the sharpness of distinction between the original colors of the dye being somewhat modified, the pile being definitely alined in an in- 40 clined direction, and the surface manifesting a satiny luster.

In order to appreciate the nature of the treatment, it is necessary to understand certain structural conditions as they exist in a 45 cut pile fabric comprising wool fibers, a chenille rug being the most typical one for present consideration.

In Fig. I, representing the untreated fabric, 1, and 2, indicate respectively two sets 50 of tufts of the pile, having contrasting, or markedly distinctive, colors, as conventionally represented by the dark shading of the tuft 1, and the absence of shading of the tuft 2. The weft threads 4, and warp threads 55 5, and 6, may be of any desired character. Upon a careful examination of such a fabric

it will be found that many integral fibers of the individual tufts lie haphazard, although there is a general slight inclination of the tufts themselves in one direction, as indicated. It will also be found that many loose fibers are disposed among the coherent ones of the tufts, as indicated in a conventional manner at 3. These fibers will be found to be highly irregular in size and to vary in 65 color, since they have become detached from most of the different colored yarns employed in the weaving. They may be likened to a tangle of loose brush and fallen branches in a forest whereof the tufts constitute the 70 main trees. It will also be found that usually there are small particles of dye-stuff entangled among the fibers.

Assuming the fabric to be in the condition described, I subject it to a bath of 75 strong soap and water, in which it is actively scrubbed and brushed, preferably by means of heavy stiff brooms, such as those employed in street cleaning. The scrubbing is conducted in all directions and it is persisted in until the loose fibers are to a great extent removed. While this is its main purpose, the washing and violent rubbing tends to modify some or all of the dyes employed, thus toning down the original sharpness of 85 the colors. I prefer to conclude this scrubbing operation by brushing the fabric for a time continuously in the direction of original inclination of the pile tufts, so as to emphasize their leaning in that direction. 90

Fig. II, represents symbolically the condition of the fabric at the conclusion of the wet scrubbing operation, where the original tufts 1, and 2, have become somewhat modified in color, the altered condition being 95 conventionally indicated at 12, and 22, respectively. The loose fibers have been largely removed and, to the extent that they remain at all, are mostly those which lie at the bottom of the tufts, as indicated at 32. The rug is then placed upon a table, or flat surface, where it is scraped, preferably by means of blocks covered with sand paper. This scraping is preferably effected throughout, substantially in the direction of original inclination of the tufts, but in any event should be conducted by application in that direction. Its main purpose and effect are to straighten out the fibers of the individual tufts, which are usually 100 more or less bound together, and to lay them over in general alinement. It thus 105 110

advantageously modifies the color effect and also emphasizes the leaning of the tufts in the same general direction. Furthermore, it tends to remove the remaining loose fibers, so that for conventional purposes, the fabric, represented in Fig. III, may be considered as free from the original loose fibers, the tufts 1—3, and 2—3, being now formed almost completely of integral fibers straightened out and lying in the same inclined direction. Thereafter the face of the fabric is pressed by means of heavy hot irons, the movement thereof being continuous in the direction of original inclination of the tufts, and the ironing process being prolonged until the fibers have been definitely alined and their ends have been turned over, forming a flattened and somewhat dense layer, as compared with the upstanding and tangled condition originally existing in the pile. After being subjected to this treatment, it will be found that the appearance of a rug whose initial colors were markedly distinct, or even harshly contrasted, has become softened throughout it by the dulling of the respective colors and the alinement of the fibers, and moreover, that the surface possesses a satiny luster comparable to that of a very fine antique oriental rug.

I am aware that it is not new to treat rugs with soap and water, and that this washing has been used to a limited extent with a view to modifying the original dyes, or at any rate with that result. Such treatment, however, has not, so far as I am aware, been pushed to the point where sub-

stantially complete removal of the superficial loose fibers is effected, nor has such removal been recognized as a desideratum. Moreover, such washing operation has not been followed by the organized scraping and ironing steps, which constitute essential features in my process.

Having thus described my invention, I claim:

The hereinbefore described improvement in the art of finishing cut pile rugs, or carpet fabrics, which consists in, first, subjecting the fabric to a bath of strong soap and water and persistently scrubbing it therein, the scrubbing movement being applied substantially in all directions across the surface; then scraping the fibers continuously in one direction, by means of sand paper, or the like, until the retained fibers of the individual tufts are substantially straightened out, and laid over in general alinement; and finally, hot pressing the surface by ironing applied in the direction of inclination of the tufts; whereby superficial loose fibers and foreign objects are removed, the remaining fibers of the tufts are laid over and the general inclination of the tufts is emphasized, and luster is imparted to the surface.

In testimony whereof I have hereunto signed my name at Philadelphia, Pennsylvania, this twenty-eighth day of July, 1915.

DAVID H. STROUD.
